WELT TURNING AND FABRIC TAKE-UP ATTACHMENT FOR FULL-FASHIONED HOSIERY KNITTING MACHINES

Friedrich Max Wachtler, West New York, and
Donald G. Trutner, North Arlington, N. J., as-
signors to Alfred Hofmann, Inc., West New
York, N. J.

Application November 15, 1939, Serial No. 304,492

55 Claims.

(Cl. 66—96)

The present invention generally relates to welt-forming and fabric take-up attachments for knitting machines and, more particularly, pertains to improvements in mechanisms for automatic welt turning and fabric take-up in the knitting of full-fashioned hosiery.

In accordance with the usual practice in the manufacture of full-fashioned hosiery, it has been customary to turn the welt manually. The manual operations involved in forming the welt require a great degree of skill, and consume considerable time. Efforts have been made towards the elimination of these drawbacks by providing automatic or semi-automatic welt turning attachments. However, such known welt turning attachments are impractical in most instances and, in all instances, are very expensive, because of their complicated and cumbersome construction and their intricate mode of operation.

It is, therefore, one of the most important objects of the invention to provide a welt turning mechanism of simplified structure and operation which may be readily attached to existing knitting machines, without necessitating material changes in the basic structure thereof and, accordingly, overcoming one of the serious objections of the trade to the adoption of automatic welt turners.

Also, in accordance with the general practice followed in the prior art, it is necessary to manually engage the take-up mechanism with each welt rod utilized to draw the fabric off the needles as knitting progresses. This operation, while not of a skillful, technical nature, demands strict and careful attention on the part of the operator and, for that reason, usually requires that the machine be stopped for the proper performance of the operation, resulting in loss of time and production.

The invention, therefore, moreover aims to provide combined welt turning and take-up mechanisms cooperatively associated for synchronized automatic function without interruption in the operation of the knitting machine, to draw the welt fabric as knitted, then turn said fabric to form a double welt, and finally draw under proper tension the stocking fabric knitted on the knitting machine subsequent to the turning of the welt.

Another important feature of the invention resides in the provision of a welt turning and fabric take-up attachment having means to assure the accurate positioning of the various operable parts for the proper turning and tension-

ing of the fabric, thus rendering the device fool-proof from a practical standpoint.

Another equally important feature of the invention resides in the provision of a combined automatic welt turning and fabric take-up attachment having a simplified construction and association of parts, and capable of being easily built into full-fashioned hosiery machines now commonly in use for cooperative function therewith to form welts and draw fabrics knitted thereby during the normal operation thereof.

Other important objects and advantages of the invention will be in part obvious and in part pointed out hereinafter.

In order that the invention and its mode of operation may be readily understood by those skilled in the art, we have, in the accompanying drawings and in the detailed description based thereupon, set out a possible embodiment of the invention.

With reference to the drawings, it is to be understood that there has been shown only those parts of a full-fashioned hosiery knitting machine which are essential to a clear comprehension of the invention, the knitting machine itself being of the usual construction and functioning in the ordinary manner well known to those skilled in the art.

In these drawings:

Figure 28 is a section taken on line 28—28 of Figure 27;

Figure 29 is a detail illustrating a constructional feature of a part of the take-up mechanism;

Figure 30 is a top plan of a part of another portion of the take-up mechanism;

Figure 31 is an enlarged perspective of a part of the welt rod holding and positioning mechanism;

Figure 32 is a section on a reduced scale taken on line 32—32 of Figure 27.

Referring more particularly to the drawings, wherein like characters of reference will indicate corresponding parts throughout, the machine frame is designated at 20 and carries the usual bearings for supporting the various shafts of the knitting machine including the rotatable longitudinally shiftable main cam shaft 21, and the rotatable hand wheel shaft 22. The machine frame is also provided with the usual center beam 23, back beam 24, front beam 25, and front table 26.

Arranged about the center beam 23 in the customary manner are the multiple knitting sections, one of which is designated in its entirety for convenience herein by the reference character 28. The knitting section 28 comprises a straight needle bar 30 with its bank of needles 32 disposed to cooperate with the presser edge 33, sinkers and dividers 34, and knockover bits 36 for the knitting of fabric in the manner well known in the art. Yarn is fed to the knitting section 28 by means of yarn carriers 38 connected to the carrier bars 40 supported in brackets 42 on the machine frame 20.

The elements so far described are found in well known knitting machines commonly used in the trade and, since their construction and operation are fully understood by those familiar with the art, an elaborate description thereof may be dispensed with herein.

In accordance with the invention, the knitting machine having the general construction hereinbefore set forth, is provided with an automatic welt turning and fabric take-up attachment, which may be stated to comprise essentially:

I. A welt bar for each knitting section.

II. A pair of welt bar carrier devices for each welt bar.

III. Mechanism for advancing and retracting the welt bar carrier devices.

IV. Mechanism for lifting, tilting, and lowering the welt bar carrier devices.

V. Means for guiding and for side-stepping the welt bar carrier devices.

VI. Automatic take-up mechanism.

VII. Welt rod supporting and positioning mechanism.

For the sake of clarity herein, each essential feature above enumerated will first be described individually in the order given, and then a general statement of operation will be made, clearly setting forth the correlated function of the various elements.

I. Welt bar

The welt bar, designated in the drawings by the reference character 44, essentially comprises complementary bar sections 46 and 47 rigidly held together by means of bolts 48, or like fastening elements, and securely clamping therebetween a bank of welt hooks 50. The welt hooks 50, which also serve as transfer elements, are adapted for cooperative action with the knitting needles 32 to receive the loops of the initial course knitted by said needles and subsequently return said loops onto the needles in the formation of the welt.

Each welt hook 50 preferably has the construction shown, consisting of a shank 52, a hook end 54, and a butt end 56, a portion of the shank and the butt end being respectively adapted to fit into a groove 58 and hole 59 formed in one section 46 of the welt bar 44. The portion of the shank 52 projecting outwardly of the clamping bar sections 46 and 47 is bent and kinked to form a double vertical bend 60, that part of the shank from a point adjacent the hook end 54 to a point adjacent the bend 60 being grooved in the usual manner for cooperation with the needle beards, as will be specified hereinafter.

The essential purposes of providing the welt hook with a double vertical bend are to form a stop for the retraction of the initial sinker loops of the welt fabric at the bend adjacent the grooved part of the shank in order to enable said initial sinker loops to line up for even and accurate transfer to the needles after the knitting of the desired length of welt fabric and in order to provide for a free passage of the needle beards through the groove of the shank for facilitating the picking up of the initial sinker loops by the needles; and to form a downward angular displacement of the grooved part of the shank as against the remaining part of the shank so that the hook is vertically downwardly displaced from the horizontal upper shank in order to enable gradual retraction of the initial sinker loops towards the loop stop bend in an upward slanting plane, during the returning motion of the welt bar for transferring said initial sinker loops onto the needles, and also to place the welt hooks into position for the return of said sinker loops to the needles by a reduced turning motion of the welt bar, whereby to limit its travel towards the sinker head, and finally, to prevent excessive stretching or dragging of initial sinker loops while retracting on the grooved portion of the shank.

In order that the welt hooks 50 may receive sinker loops of the initial course knitted by the needles 32, and subsequently return said loops to the needles, the welt bar 44, according to the present invention, is capable of going through a sequence of movements. In describing the movements of the welt bar, the terms "forward"

and "backward" are used with respect to the welt bar itself, the welt hooks being regarded as located at the welt bar front which normally is disposed to face the needles from the front of the machine frame. Therefore, the term "forward" indicates the movement of the welt bar in a general direction from the front to the back of the machine, whereas the term "backward" indicates the movement of the welt bar in a general direction from the back towards the front of the machine frame. When referring to the placement of the welt hooks behind the needles, the term "behind" is used with respect to the forward movement of the welt bar, which forward movement is employed for the presentation of the welt hooks to the needles. Therefore, the term "behind" indicates the location of the welt hooks on the bearded side of the needles between the latter and the presser edge.

The sequence of the welt bar movements is illustrated in Figures 13 to 25 inclusive. As shown in Figure 13, the welt bar first undergoes a rectilinear horizontal forward movement to advance the welt hooks towards the needles for bringing said hooks from an inactive to an active position, the welt bar being guided during a part of said movement for so positioning the welt hooks in relation to the needles that during the continued rectilinear forward movement of the welt bar, the hook ends of said welt hooks will pass between the needles in line with the sinkers at a point between the sinkers and the knockover bits to engage the initial sinker loops when they are cast off the sinker nibs.

As shown in Figure 14, the welt bar then undergoes a rectilinear horizontal backward movement to retract the welt hooks away from the needles after engaging the sinker loops and, accordingly, draw the welt fabric under tension while being knitted.

As shown in Figure 15, the welt bar then undergoes a rectilinear slanting upward movement towards the needles to turn the welt fabric and bring the hook ends of the welt hooks on a plane above the heads of the needles, the welt bar being shifted during a part of this movement to side-step the welt hooks for their alignment with the needles.

As shown in Figure 16, the welt bar then undergoes a curvilinear substantially forward movement towards the needles to cause the vaulting of the welt hooks over the needles and continuing in a curvilinear substantially downward movement to place said welt hooks behind the needles that is, on the bearded side thereof where said hooks are held stationary until the needles go into position preparatory to the transfer of the initial sinker loops back onto the needles.

As shown in Figure 17, the welt bar then undergoes a rectilinear substantially downward movement to bring the initial sinker loops adjacent to the needle heads at a point between the knockover bits and the sinkers to place said loops in position for engagement by the needles, after which the needles rise and enter said initial loops (Figure 18).

As shown in Figure 19, the welt bar then undergoes a substantially rectilinear backward movement whereby the welt hooks follow the movement of the needles for placing the same in position preparatory to the unhooking movements.

As shown in Figure 20, the welt bar then undergoes a substantially rectilinear vertical upward movement cooperating with the needle motion,

eventually bringing the loops under tension between the sinkers and the hook ends of the welt hooks.

As shown in Figure 21, the welt bar then undergoes a thrust forward movement bringing the hook ends of the welt hooks into a substantially horizontal position preparatory to unhooking.

As shown in Figures 22 and 24, the welt bar then undergoes a slightly vertical downward movement causing the bent points at the hook ends of the welt hooks, as best shown in enlarged Figure 24, to slip past the beards of the needles, thus relieving the tension of the initial sinker loops for the instantaneous disengagement of the hooks from said loops.

The movement separately illustrated in Figures 21 and 22 are more or less simultaneous so that the positioning of the hook ends into a substantially horizontal plane, the relieving of the tension on the transferred loops, and the unhooking of the welt hooks from said loops follow in rapid succession, in the manner represented in Figure 25.

As represented in Figure 23, the welt bar then undergoes a rectilinear horizontal backward movement away from the needles to move the welt hooks out of the knitting field; a curvilinear tilting backward movement away from the needles to place the welt hooks in their normal position in a substantially horizontal plane; and, finally, a rectilinear horizontal backward movement away from the needles to return the welt hooks to their original inactive position.

From the foregoing, it will be understood that, in accordance with our improved method, the movements of the welt bar may be divided into three distinct groups, as follows:

1. Movements to effect the bringing of the welt bar from an inactive to an active position for the hooking up of the welt hooks with the initial sinker loops, and for the drawing of the welt fabric under tension while being knitted (Figures 13 and 14).

2. Movements to effect the turning of the welt fabric and the transferring of the initial sinker loops back onto the needles (Figures 15, 16, 17, 18, and 19).

3. Movements to effect the unhooking or releasing of the welt hooks from the initial sinker loops after their transfer onto the needles and the returning of the welt bar to inactive position (Figures 20, 21, 22, and 23).

Attention is particularly called to the fact that the movement of the welt bar for the positioning of the hook ends on a substantially horizontal plane is possible because of the particular formation of the welt hooks, that is to say, the angular relationship of the bent portions of the shanks are such that the sinker head and other parts of the machine will not prevent or interfere with the movement of the welt bar to its tilting limit for positioning the hook ends on a substantially horizontal plane, as aforesaid.

Also, it is to be noted that the pivot point about which the welt bar swings in its movements to relieve the tension on the loops transferred onto the needles and unhook the welt hooks from said loops, is located, as shown at X, in Figure 23, in front of the welt bar proper and below the center thereof, thus enabling the welt bar to vault over the needles gradually in a curvilinear motion with a minimum lift of the welt bar and, at the same time, reducing the forward travel of the welt hooks to a minimum to prevent possible inter-

ference with existing parts on the knitting machine.

In accordance with the present invention, all the foregoing enumerated movements are preferably automatic, with the exception of the first setup movement which may be accomplished by manual control, in the manner to be explained more fully hereinafter.

In order that the welt bar 44 may go automatically through its various rectilinear and curvilinear movements, the invention contemplates the provision of devices and mechanisms cooperatively associated for synchronized automatic function, which devices and mechanisms will now be described.

II. Welt bar carrier devices

For the purpose of supporting the welt bar 44 so that it may receive its various movements, there are provided two carrier devices 62, one for each end of said welt bar. Each carrier device 62 preferably comprises a supporting slidable plate 64 upon which is mounted for vertical oscillating movements a lever arm 66 pivoted at its intermediate portion on a stud 68 provided on said supporting slidable plate. Each lever arm 66 is held resiliently in normal horizontal position by means of a spring 70 constantly urging the outward end 72 of said arm in contact with a stop 74 of the associated supporting plate 64. The inward end 76 of each lever arm 66 is provided with a pivot stud 78 passing through an opening 80 of a tiltable swingable welt bar holding member 82 preferably having the general shape fully shown in Figure 10.

Each member 82 is formed with a rearward extension 84 to which the corresponding extremity of the welt bar 44 is affixed, for instance, by means of a bolt 86, as more clearly represented in Figures 6 and 7. The tilting swinging movement of the members 82 in the direction of arrow A (Figure 7) may be limited by providing on the lever arms 66 abutments 88 disposed to contact with the underside of extensions 84 of said members. Each member 82, moreover, is formed with a pair of forward extensions 90 and 92 respectively having camming surfaces 94 and 96, for the purpose to be hereinafter specified.

III. Mechanism for advancing and retracting the welt bar carrier devices

Suitably fixed in relative spaced relation along the front table 26 are pairs of bearing brackets, such as that represented at 100, which brackets support a rotatable shaft 102 extending throughout the length of the knitting machine. Mounted for free rotation upon the shaft 102 within the confines of each knitting section 28 is a pair of hollow casings 104 preferably of circular configuration and each, as more clearly shown in Figure 12, having a bore 106 suitably formed in the peripheral surface thereof and opening therein.

Received within the bore 106 of each casing, and rigidly connected thereto, is one end 108 of an elongated channeled rail 110 disposed so that the intermediate portion 112 extends transversely of the front table 26 and its free end 114 projects towards the needle bar 30.

As represented in the drawings, the portion 112 of each rail 110 transversely extending over the front table 26 may be provided with a lateral lug 116 carrying an adjustable abutment 118 normally adapted to rest upon said table and thus regulate the vertical normal position of the

75 rail 110 in relation to the needle bar 30. The casings 104 within the confines of each knitting section 28 are so located on the shaft 102 that the free ends 114 of the rails 110 lie in substantial transversal alignment with the opposite extremities of the corresponding needle bar 30. This location of the casings 104 may be fixed by their abutment against the bearing brackets 100.

Associated with each casing 104 and freely engaged on the shaft 102, as will more clearly appear from Figures 11 and 12, is a disc 120 of a size to fit concentrically within the hollow portion of said casing. The inner face of each disc 120 enclosed in the casing 104 is formed with an inner groove 123 and an outer groove 123a interconnected by means of a passage 124 cut on a line tangent to the inner groove through the portion 125 separating said grooves. A flexible cable 126 preferably in the form of a coil spring is nested within the grooves 123 and 123a, one end portion 128 of said cable being retained securely within the inner groove 123 by means of an annular plate 130 suitably fixed to the disc 120, for instance, by bolts 132 or like fastening elements.

Arranged adjacent the outer face 134 of each disc 120, and keyed to the shaft 102, as shown at 136, is a clutch member 138 provided with a spring pressed rotatable plunger 140 normally adapted for engagement with an opening 142 cut into said disc 120, whereby rotation of the shaft 102 in the direction of arrow B or in the direction of arrow C will be transmitted to said disc 120 and, accordingly, wind or unwind the associated flexible spring cable 126. The free end 144 of each flexible spring cable 126 is introduced into the corresponding channeled rail 110 to slide freely therein, and is connected to a plunger 146 rigidly attached, by means of pins 148 or like fastening elements, to the respective supporting slidable plate 64 of each of the welt bar carrier devices 62.

Because of the provision of the clutch arrangement, it will be understood that the mechanism for advancing and retracting the welt bar devices 62 within the confines of any one of the knitting sections 28 may be rendered inoperative at will.

From the foregoing description, it will be understood that when the clutch members 138 are in active engaged position, rotation of the shaft 102 in the direction of arrow B will cause the welt bar 44 to move away from the needle bar 30, whereas rotation of the shaft 102 in the direction of arrow C will cause the welt bar to move towards the needle bar.

Automatic rotation of the shaft 102 in the direction of arrow B, which is utilized to slide the welt bar 44 away from the needles for drawing the welt fabric as the knitting of courses progresses, may be, and preferably is, accomplished by means of a pulley or drum 150 affixed to said shaft, and of a take-up-cable 152 mounted thereabout, said cable being maintained under constant pulling tension, for example, by passing in the usual well known manner over an overhead pulley and thence down to a counterweight (not shown).

Automatic rotation of the shaft 102 in the direction of arrow C, which is utilized to slide the welt bar 44 towards the needle bar for turning the welt fabric and transferring the initial sinker loops onto the needles is had by means of a racking mechanism 154 comprising, as more clearly shown in Figures 3 and 4, a pinion 156

keyed, or otherwise affixed, to said shaft 102 and a reciprocating rack 158 enmeshed with said pinion. The rack 158 may be guided in its reciprocating movements by enclosing the same within an elongated casing 160 conveniently supported on the shaft 102 and having a portion 162 adapted to constitute a housing for the pinion 156. The upper end of the casing 160 is provided with a spring pressed plunger 157 adapted for engagement with the adjacent end of the rack 158 to act thereon in the manner, and for the purpose, to be specified hereinafter.

Connected to the rack 158, for instance as shown at 164, is a rod 166 passing freely through an opening 168 in one end portion 170 of an oscillating lever 172, having its other end portion 174 affixed to a rocking shaft 176 supported in bearing brackets 178 on the back beam 24 of the machine frame 20. A collar 180 adjustable along the length of the rod 166 is provided to form an abutment for the lever 172 so that the latter, in its oscillating movement, may lift the rack 158 from the position shown in Figure 2 to the position shown in Figure 3, as and for the purpose to be explained hereinafter.

Also affixed to the shaft 116 is a second lever 184 carrying a shiftable roller 186 adapted for riding engagement either with an idling cam 188 or an active cam 190 on the main cam shaft.

As will more clearly appear from Figure 1, the shiftable roller 186 is associated with a forked shifter 192 pivoted, as shown at 194, on a suitable support 196 on the machine frame 20, and resiliently connected, as shown at 198, to a shifting rod 200 controlled by the well known pattern mechanism of the knitting machine at the time when the automatic turning of the welt is to be effected in accordance with the mode of operation which will be described in detail hereinafter.

The welt bar may also be moved towards the needle bar for the hook-up operation, that is, to bring the welt hooks 50 in position adjacent the needles 32 for engaging the initial sinker loops by manually rotating the shaft 102 in the direction of arrow C. The manual rotation of the shaft 102 is possible because of the loose connection between the rack 158 and its operating lever 172.

For the purpose of assuring the accurate positioning of the welt hooks 50 in relation to the needles 32, and also prevent the tips of said hooks from injury by ramming into parts of the knitting machine, such as the presser edge 33, when moving the welt bar towards the needle bar, there may be provided a limit stop 202 preferably consisting of a one-tooth ratchet wheel 204 affixed to the shaft 102 and adapted to be engaged by a dog 206 conveniently mounted on a suitable portion of the rack casing 160. This dog 206 may be moved manually by the operator into contact with said wheel 204 as the welt hooks 50 approach the needles 32 so that, with the following rotation of the shaft 102 in the direction of arrow C, the tooth 208 of said wheel 204 will abut the end 210 of the dog and, accordingly, arrest further movement in that direction.

In order to assure the release of the shaft 102 for the subsequent operation of the mechanism, there may be provided a rod 212 connected, as shown at 214, to the cam operated lever 172 and having a connection 216 with the dog 206 whereby, upon upward movement of said lever, the dog will be lifted to disengage the tooth 208 of the

ratchet wheel 204, as indicated in full lines in Figure 3 of the drawings.

In order that the mechanism may be adaptable to form welts of various widths, there may be provided means capable of limiting movement of the rack 158 which, accordingly, limits the drawing of the welt bar 44 away from the needle bar 30. Such a possible means has been shown in Figures 3 and 4 wherein a dog 218 is pivotally mounted in the casing 160 and adapted to be manually actuated by means of a handle 220 for positioning in the path of movement of a recessed portion 222 on said rack 158.

IV. Mechanism for lifting, tilting, and lowering the welt bar carrier devices

In order to position and actuate the welt bar 44 to effect the complete turning of the welt, there is provided the following mechanism.

Mounted on the machine frame 20 to extend between, and in substantial alignment with, the front table 26 and needle bar 30, is a rockable shaft 224 of a length sufficient to extend throughout the length of the knitting machine. Carried by the shaft 224 for rocking movement therewith are pairs of spaced sectional operating devices 226, one pair of such devices being arranged within the confines of each knitting section and one device being associated with each channeled rail 110.

Each sectional operating device 226 preferably consists of a split hub 228 formed with an extension arm 230, and of a link 232 pivoted at its intermediate portion by means of a pivot stud 234 to said extension arm 230. The stud 234 also carries a roller 236 positioned to contact the underside of the associated channeled rail 110, as more clearly indicated at 238 in Figure 7 of the drawings. The link 232 is formed with a substantial straight finger 240 and an angularly bent finger 242. The straight finger 240 is urged, by means of a spring 244, to bear upon a cam shaped stop 246 adjustable on the extension arm 230 to set the position of the link 232 in relation to said extension. The angularly bent finger 242 is disposed to engage the camming face 94 or 96 on the extension 90 or 92 of the associated welt bar holding member 82, depending upon the position of said member, to swing the same in the manner to be set forth in the subsequent description of its operation.

Also secured to the shaft 224 is a lever 248 connected by means of a link 250 to one end 252 of an arm 254, having its other end 256 pivoted to the machine frame, as shown at 258. The intermediate portion of the arm 254 carries a shiftable roller 260 intended for riding engagement either with an idling cam 262 or an active cam 264 on the main cam shaft 21. The roller 260 is associated with a forked shifter 266 pivoted, as shown at 268, on a suitable support 270 on the arm 254, and resiliently connected, as shown at 272, to the shifting rod 200 which, as hereinbefore stated, also controls the shifter 192. Thus, when the roller 260 is in engagement with the active cam 264, said cam will act through the arm 254, link 260, and lever 248 to rotate the shaft 224 in the direction of arrow D and, accordingly, bring the roller 236 in contact with the associated channeled rail 110 and lift the same, together with the welt bar 44, and to place angular bent finger 242 into position to cooperate with extensions 94 and 96 of the holding and turning member 82, on which welt bar is mounted for the turning operation by the forward movement of the welt bar.

V. Means for guiding and side-stepping the welt bar carrier devices

In order to effect the proper initial hook-up, the welt bar 44, in moving at its lowermost level towards the needle bar 30, is guided so that the welt hooks 50 may pass between the needles 32 in line with the sinkers 34 at a point between the sinkers 34 and the knockover bits 36, to engage the initial sinker loops when they are cast off the sinker nibs; also, in order to effect the proper return of said initial sinker loops to the needles subsequent to the knitting and turning of the welt fabric, the welt bar 44, in moving at its uppermost level, is side-stepped to align the welt hooks 50 with the needles. Although various means may be employed for guiding and side-stepping the welt bar, the mechanism 274 illustrated in the drawings is preferred. This mechanism 274 comprises supporting brackets 276 rigidly mounted on the brackets 100 and located adjacent the path of movement of the supporting slideable plates 64. Stud-headed pins 278 and 280 are adjustably carried by each of said brackets 276, the pins 278 being disposed to contact said slideable plates 64 when moving in lowered position, and the pins 280 being disposed to contact the slideable plates when moving in elevated position. The mentioned side-stepping is made possible because of the normal working clearances of the various parts of the mechanism.

VI. Automatic take-up mechanism

In order to draw the welt fabric from the needles 32 and maintain said fabric under tension during the turning of the welt, and finally withdraw the fabric knitted by the machine after the turning of the welt, there is provided a take-up mechanism which is intended to co-function with the welt turning mechanism.

The fabric take-up mechanism includes a shaft 282 rotatably supported in suitable bearing brackets 284 on the machine frame 20 in a plane parallel, but offset in relation to, that of the shaft 102 of the welt turning mechanism.

Freely mounted upon the shaft 282 and held by means of collars 286 within the confines of each knitting section 28, is a pair of hollow casings 288 preferably of circular configuration and each having a bore 290 suitably formed in the peripheral surface thereof and opening therein.

Received within the bore 290 of each casing 288 and rigidly connected thereto is one end 292 of a slotted tube 294 disposed so that its intermediate portion 296 extends transversely of the front table 26, and its free end 298 projects towards the needle bar 30. As shown in the drawings, the portion 298 of each slotted tube 296 extending over the front table 26 may be fixed thereon by means of a clamp 300.

Associated with one of the casings 288 of each pair, and fixed upon the shaft 282, for instance, by means of a lock screw 302, is a sleeve 304 having a flanged portion 306. A hub 308 is freely received on the sleeve 304 and abuts the flanged portion 306 thereof. The surface of the hub 308 abutting the flanged portion 306 of the sleeve 304 is formed with an annular recess 310 accommodating an adjustable stop 312 and a fixed stop 314 relatively disposed at diametrically opposed points on said flanged portion 306. The hub 308 is moreover provided with a pin 316 projecting into the recess 310 and adapted to contact the fixed stop 314 on the flanged portion 306 of the sleeve 304, a spring 318 being interposed between said

pin and adjustable stop carried by said flanged portion.

By reason of this construction, it will be appreciated that the hub 308 is capable of torsional resiliency, which is desirable to assure the proper take-up operation, as will fully be pointed out hereinafter.

The hub 308 with its torsional resilient construction cooperates with a second hub 320 freely mounted on the shaft 282 to support a ware-roller 322, said second hub being associated with the remaining casing 288. Each hub 308 and 320 is formed with a pulley-like extension 324 enclosed in the associated casing and having a flexible cable 326 preferably in the form of a coil spring wound thereabout. One end portion 328 of each of the flexible cables 326 is fixed to the extension 324 of the corresponding hub, as shown at 330, and the other end portion 332 of each spring cable 326 passes in the associated slotted tube 294. The spring cables 326 are interconnected by means of a cross bar 334 consisting of solid end pieces 336 united to the free ends of said cables, and of an intermediate tubular piece 338 engaging said end pieces. Hooks 340 are rigidly attached to the solid end pieces 336 and engageable with a welt rod 342 adapted to be laid over the welt fabric.

From the preceding description of the take-up mechanism, it will be understood that rotation of the shaft 282 in the direction of arrow E will wind the spring cables 326 and, accordingly, draw the hooks 340 and welt rod 342 in engagement therewith away from the needle bar 30, whereas the turning of the shaft 282 in the direction of arrow F will unwind the spring cables 326 and cause the hooks 340 to move towards the needle bar.

By reason of the spring 318 and its association with the ware-roller construction, it will be understood that said spring will cooperate with the spring cables 326 to maintain the fabric under constant proper tension while affording sufficient torsional resiliency to assure free movement of the knitting needles 32 in the various functions thereof.

Automatic rotation of the shaft 282 in the direction of arrow E which is utilized to maintain the fabric being knitted under proper tension and take up the same as knitted by the machine, is accomplished by means of a pulley or drum 344 affixed to said shaft and having a take-up cord 346 wound thereabout, said cord being maintained under constant pulling tension by passing in the well known manner over an over-head pulley and thence down to a counterweight (not shown). A handle and ratchet device 340 is shown for turning the drum 344 to wind up the cord 346 thereon in order to provide sufficient draw-off movement by weight action.

Automatic rotation of the shaft 282 in the direction of arrow F, which is utilized to release the tension on the fabric in order to allow for the turning of the welt, is had by means of a racking mechanism 350 comprising a pinion 352 affixed onto the shaft 282, and a rack 354 engageable with said pinion. The rack 354 is provided with an extension 356 having a slide 358 engageable with a pin 360 rigid with the welt bar mechanism operating arm 173 so that, upon oscillation of said arm, the rack 354 will be reciprocated to rotate the pinion 352. The rack 354 is resiliently maintained in engagement with the pinion 352 by operation of the guide member 362 cooperating with grooved collar 370 fixed on

the shaft 282. Guide member 362 is pivoted at 364 to projection 366 on extension 356, and is maintained parallel, or in other suitable predetermined relationship, to rack 354 by stop pin 367 fixed in the upper extremity of guide member 362 which is constantly urged in bearing contact with the end of rack 354 by spring 368. The guide member 362 is provided with a recessed portion 372 intended to register with the grooved bushing 370 on the shaft 282 when the rack 354 reaches its lowermost position (Figure 2), whereby said rack will be caused to disengage the pinion 352.

The welt rod hooks 340 may also be brought into their position adjacent the needle bar 30, that is, to the position shown in dotted lines in Figure 26 of the drawings, by manually rotating the shaft 282 in the direction of arrow F, which is possible because the rack 354 is then out of engagement with the pinion 352, as shown in Figure 2.

The proper position of the hooks 340 is assured by means of a one-tooth ratchet wheel 274 on the shaft 282, to be engaged by a dog 276 pivotally supported on a suitable portion of the machine frame 20, which dog 276 may be operated in the same manner as the dog 206 hereinbefore referred to.

At this point, attention is called to the fact that the hooks 340 are maintained advantageously above the fabric and its knitting field by means of a bend 378 in the slotted tubes 294 which guides the hooks upwardly. At any time after a sufficient amount of welt fabric has been knitted, the welt rod 342 may be brought by the operator into operative position.

VI. Welt rod supporting and positioning mechanism

To eliminate the separate manual placing of individual welt rods, a convenient auxiliary attachment 380 for handling the welt rods of all the knitting sections is provided. As shown in the drawings, this auxiliary attachment 380 preferably comprises spring clips 382 one for each end portion of each welt rod to frictionally engage the same in the manner indicated particularly in Figure 31.

Each clip 382 is carried on a head 384 having rod guiding members 386. The heads 384 are secured to a cross bar 388 supported in arms 390 swingable over and back to operative position, as represented in Figure 26. For that purpose, the arms 390 are mounted for swinging movement on pivots 392 in bearing supports 394 on the brackets 100 over the front table 26 of the machine frame 20, and operable to bring a series of welt rods simultaneously above the fabric being knitted in the various knitting sections. In this manner, it will be appreciated that the welt rods are suspended over the fabrics in the path of movement of the hooks 340 when retracted. The suspended position of the welt rods may be accurately adjusted by means of adjustable stops 396 on the arms 390 and disposed to contact with the bearing supports 394.

Operation

In using the improved welt turning and fabric take-up attachment, the initial course of loops is formed by operation of the knitting machine in the usual manner, that is, the yarn carriers 38 feed the yarn to the needles 32 which then co-function with the sinkers and dividers 34 to form the loops which remain engaged on the needles.

Following the formation of said initial course of loops, the knitting is stopped, or at least slowed down, for permitting the welt hooks 50 on the welt bar 44 to enter between the needles 32 in line with the sinkers 34 at a point between the sinkers 34 and knockover bits 36 (Figure 13), and subsequently receive the initial loops when cast off the sinker nibs. Thereafter, the welt bar is retracted from the hook-up position (Figure 14) to produce the desired tension, whereupon the knitting of the welt fabric can continue.

The welt bar 44 which, during the knitting of the initial course, laid in its neutral inactive position, that is, away from the needles and in a substantially horizontal plane, is given its rectilinear horizontal forward movement towards the needle bar 30 and brought into operative hook-up position, that is, with the hook ends 54 of the welt hooks 50 projecting slightly beyond the needles 32 in line with the sinkers 34 at a point between the sinkers 34 and knockover bits 36. The welt bar 44 is moved towards the needle bar for the hook-up operation by manually rotating the shaft 102 as hereinbefore stated. The movement of the welt bar towards the needle bar for the hook-up operation takes place with the channelled rails 110 and the welt bar carrier devices 62 at the lowest level due to the lowered position of the rollers 236 carried by the sectional operating members 226 on the shaft 224 under control of the cam roller 260, which at this time engages the idling cam 262 on the main cam shaft 21. In this position, the rails 110 with the welt bar carrier devices 62 are vertically located by the abutments 118 contacting the front table 26.

As the welt bar 44 approaches the needle bar 30, said welt bar is guided in its rectilinear forward horizontal movement by the stud-headed pins 278 contacting the slideable plates 64 which, as already mentioned, places the welt hooks 50 for passage between the needles 32 in line with the sinkers 34 at a point between the sinkers 34 and knockover bits 36 to effect the hook-up with the sinker loops of the initial course when cast off the sinker nibs.

Following the hook-up, the knitting machine operates in the usual manner to knit the series of courses forming the welt fabric, which is drawn resiliently through the welt bar 44 and associated spring flexible cables 126 by means of the drum 150 and take-up cable 152 functioning to rotate the shaft 102 in the direction of arrow B, which imparts to the welt bar its rectilinear horizontal backward movement away from the needles.

As the knitting of the welt proceeds, the welt rod hooks 340 are brought to their position adjacent the needle bar 30, that is, the position shown in dotted lines in Figure 26, by manually rotating the shaft 282 in the direction of arrow F. At any time after a sufficient amount of welt fabric has been knitted, the welt rod 342 may be brought by the operator into operating position by actuating the welt rod supporting and positioning mechanism.

As the end of the knitting of the welt approaches, the shaft 282 is rotated manually in the direction of arrow E, which resiliently retracts the hooks 340 from their position adjacent the needle bar. The hooks 340, in their retracting movement, engage the associated welt rod 342, freeing the same from the spring clips 382 and, through action of the bend 378 in the slotted tube 294, draws said rod 342 onto the fabric. The

welt rod 342 is drawn to a point where it underlies the welt bar 44; thus the loops engaged on the welt hooks are gradually retracted towards the loop stop bend 60 of the welt hooks and become finally lined up in positive engagement with said bend 60.

Also, the drawing of the welt rod to the point mentioned results in resiliently exerting a pull on the welt fabric, replacing the pull exerted through the welt bar, until the full desired length of fabric is attained.

About the time the knitting has progressed to a point approximately three courses prior to the end of the welt fabric knitting, the well known pattern chain mechanism of the machine operates to actuate the shifting rod 200 which pivots the forked shifters 192 and 266, causing the rollers 186 and 260 to shift on their idling cams 190 and 264. At that same time, the pattern chain of the machine also operates to actuate a switch control (not shown) having the usual well known construction, and operating to set the machine into low speed, which is desirable to effect the turning of the welt. The knitting machine thus set, continues to knit the last courses of the welt fabric, whereupon the pattern chain mechanism operates to actuate the ordinary main cam shaft shifting mechanism to move the cam shaft 12 to narrowing position and, accordingly, bring the active cams 190 and 264 into aligned relationship with the corresponding rollers 186 and 260 of the mechanism.

It will be understood that the shifting of the main cam shaft likewise brings into play a different set of operating cams to work the needles 32, 35 sinkers and dividers 13 and knockover bits 36.

With the active cams 192 and 264 in engagement with the rollers 186 and 260, the machine functions to turn the welt and transfer the initial sinker loops back onto the knitting needles in the 40 following manner:

Rotation of the main cam shaft 12 causes the cam 190 through the roller 186, lever 184, shaft 176, and lever 172 to actuate the racking mechanisms 154 and 350 in unison, causing the simultaneous rotation of the shafts 102 and 282 in the direction of arrows C and F respectively which, as hereinbefore stated, moves the welt bar 44 and welt rod 342 towards the needle bar 30. At substantially the same time, the cam 264 through 50 the roller 260, arm 254, link 250, and lever 248 rotates the shaft 224 in the direction of arrow D, accordingly raising the sectional operating devices 226 so that, with the continued movement of the welt bar 44 towards the needle bar 30, the underside of the rails 110 will ride over the rollers 236, thus elevating the welt hooks 50 to the latter on a plane above the knitting needles (Figure 15). As the welt hooks 50 are elevated to their position above the knitting needles the welt bar 60 44 is shifted to align said hooks with the needles. This is done by means of the stud-headed pins 280 carried by the brackets 276 and adapted to contact the supporting slidable plates 64, thus guiding the welt bar supporting structure to position the welt bar hooks as stated.

By the time the welt hooks 50 reach their elevated position, shown in Figure 15, the sinkers and dividers 34 have retracted, and the needles 32 start their movement from the position shown 70 in Figure 15 to the position shown in Figure 16. At about the same time, the camming faces 96 of the forward extensions 92 of the welt bar supporting members 82 come in contact with the bent fingers 242 of the sectional operating devices 75

226 on the welt bar lifting and tilting mechanism so that, during the continued forward movement of the welt bar 44, the same is given a curvilinear movement causing the welt hooks to vault over the needles going through the successive positions shown in Figure 16 of the drawings.

The tilting of the welt bar 44 in its curvilinear movement ultimately places the welt hooks 50 in the position represented in full lines in said Figure 16, wherein said hooks are shown as adjacent to the presser edge 33 having been hurdled over the tips of the needles 32 and brought down and held behind them, that is, on the beard side of said needles in preparation for the loop transfer, whereupon the needles 32 are brought back in the direction of the sinker head entering the grooves of the welt hook shanks 52 (Figure 17). The resilient mounting through spring 244 of the link 232 assures the positive interengagement of the welt hooks 50 and needles 32 during the various movements thereof to effect the actual loop transfer. The welt hooks and needles being thus coupled, the latter are operated to enter the loops on the former (Figure 18), the fabric being held down not merely by the bends 60 in the hooks, 25 but also by the sinkers and dividers 34 which are then in their advanced position. Now with the loops engaging both the hooks 50 and needles 32, the needles and the hooks shift to the position represented in Figure 19.

Thereupon, the welt bar and hooks are lifted to the extent that the hook ends 54 of the welt hooks are brought up to the loops which surround the hook shanks (Figure 20). At this moment, sharp risers 190a and 264a in the cams 190 and 264 come into action sharply lifting the rack 158 and rails 110, causing a compression of the plunger 157 and spring 70 and tensioning the spring 244 while, at the same time, tilting the welt bar 44 to its limit, thus (as best shown in Figure 25) imparting a combined thrust forward movement and slightly vertical downward movement to said welt bar and bringing the hook ends 54 to a substantially horizontal plane so that, immediately upon the passing of said sharp risers, the welt bar will snap back, bringing about the positive disengagement of the hooks from the loops. Immediately upon disengagement of the hooks from the loops, the welt bar starts to recede, the camming faces 94 of the extensions 90 on the welt bar holding members 82 coming in contact with the bent fingers 242 which return the welt bar 44 and welt hooks 50 to their original horizontal position, as shown in Figure 23, the welt bar being then drawn away from the needles until it reaches its initial position where it remains until another welt turning operation is to be performed.

It will be appreciated that as the welt bar 44 and welt rod 342 go through their various movements, the fabric is held constantly under proper yieldable tension due to the provision of the spring cables 126 and 326 and also of the torsional spring 318 associated with the ware-roller 322.

When the welt bar has reached its initial position following the turning of the welt, the pattern chain mechanism acts to restore the machine to normal knitting position, whereupon knitting of the leg portion of the stocking is carried out in the usual manner, the fabric being drawn through the take-up mechanism which then operates by actuation of the take-up drum 344.

In concluding, it is to be understood that the

construction herein shown and described is capable of certain modifications without departing from the essence of the invention. Accordingly, any modifications coming within the scope of the subjoined claims are to be considered within the spirit of the invention.

What we claim is:

1. In combination with the bank of needles of a flat knitting machine, a welt turning mechanism comprising: a welt bar; supporting means therefor; means operable to advance said welt bar and its supporting means towards the needles; and means operable for placement in the path of the welt bar supporting means for imparting a tilting swinging motion to the welt bar in its advance towards the needles a fabric draw-off device including a fabric draw-off member and means to move said draw-off member in a direction opposite to that of its draw-off movement; and, means operable for automatically actuating the draw-off member moving means simultaneously with the movement of the welt bar in the direction towards the needles.

2. In combination with the bank of needles of a flat knitting machine, a welt turning mechanism comprising: a welt bar; carrier devices slidable towards and away from the needles and including pivotal members on which the welt bar is mounted to receive bodily tilting movements in reverse directions; swinging guides on which the carrier devices are slidably mounted to receive their sliding movements towards and away from the needles; and cam operated devices having means in engagement with said guides for shifting the same to raise the welt bar above said needles and further having means engageable with said members of the carrier devices to impart tilting and swinging movements to the raised welt bar during the sliding movement of the carrier devices on said guides in the direction towards the needles; a fabric draw-off device including a fabric draw-off member and means to move said draw-off member in a direction opposite to that of its draw-off movement; and, means operable for automatically actuating the draw-off member moving means simultaneously with the sliding movement of the carrier devices on said guides in the direction towards the needles.

3. In combination with the main cam shaft and knitting needles of a flat knitting machine, a welt turning mechanism comprising: a welt bar; carrier devices, one for each end of the welt bar, and mounted for rectilinear movements towards and away from said needles; and a mechanism under control of said main cam shaft to impart curvilinear movements to said carrier devices for causing the welt bar to move over and behind the needles in the course of the rectilinear sliding movements of said carrier devices toward the needles; a fabric draw-off device including a fabric draw-off member and means to move said draw-off member in a direction opposite to that of its draw-off movement; and, means under control of the main cam shaft for automatically actuating the draw-off member moving means simultaneously with the movement of the welt bar in the direction towards the needles.

4. In combination with the main cam shaft and knitting needles of a flat knitting machine, a welt turning mechanism comprising: a welt bar; supporting means therefor; means operable to advance the welt bar and its supporting means towards said needles; means operable for placement in the path of the welt bar supporting means for imparting a tilting, swinging motion

to the welt bar in its advance towards said needles; and a mechanism under control of said main cam shaft for operating the last mentioned means; a fabric draw-off device including a fabric draw-off member and means to move said draw-off member in a direction opposite to that of its draw-off movement; and, means under control of the main cam shaft for automatically actuating the draw-off member moving means simultaneously with the movement of the welt bar in the direction towards the needles.

5. In combination with the main cam shaft and knitting needles of a flat knitting machine, a welt turning mechanism comprising: a welt bar; carrier devices slidable towards and away from the needles and on which said welt bar is mounted to receive bodily tilting movements in reverse directions; swinging guides on which the carrier devices are slidably mounted to receive their sliding movements towards and away from said needles; and mechanism under control of said main cam shaft and engageable with said guides for shifting the same to raise the welt bar above the knitting needles and imparting tilting and swinging movements to the welt bar; a fabric draw-off device including a fabric draw-off member and means to move said draw-off member in a direction opposite to that of its draw-off movement; and, means under control of the main cam shaft for automatically actuating the draw-off member moving means simultaneously with the movement of the welt bar in the direction towards the needles.

6. In combination with the pattern control mechanism and knitting needles of a flat knitting machine, a welt turning mechanism comprising: a welt bar; supporting means therefor; means operable to advance said welt bar and its supporting means towards the needles; means operable for placement in the path of the welt bar supporting means for imparting a tilting swinging motion to the welt bar in its advance towards the needles; and a mechanism operated by said pattern control mechanism for operating the last mentioned means; a fabric draw-off device including a fabric draw-off member and means to move said draw-off member in a direction opposite to that of its draw-off movement; and, means under control of the main cam shaft for automatically actuating the draw-off member moving means simultaneously with the movement of the welt bar in the direction towards the needles.

7. In a flat knitting machine: a welt bar; a pair of welt bar carrier devices, one for each end of the welt bar, each of said carrier devices including a welt bar holding member, a lever arm carrying said member for tiltable swingable motion, and a plate supporting said arm; a mechanism for advancing and retracting said welt bar carrier devices and including a flexible cable for, and attached to, each supporting plate of each welt bar carrier device, an elongated channeled rail partly enclosing said cable, a casing mounted for rocking movement and carrying said rail, a drum within the casing and connected to said cable for winding and unwinding the same, a racking device for operating said drum to wind and unwind the cable, and a power driven means for actuating said racking device; a mechanism for lifting, tilting, and lowering the welt bar carrier devices including a welt bar operating device for each welt bar carrier device and having means engageable with the welt bar holding member thereof for tilting and swinging said member together with the welt bar, and means in engage-

ment with the corresponding rail of the welt bar carrier advancing and retracting mechanism for lifting and lowering the same; and a power driven means for actuating said welt bar actuating devices; a fabric draw-off device including a fabric draw-off member and means to move said draw-off member in a direction opposite to that of its draw-off movement; and, means for automatically actuating the draw-off member moving means simultaneously with the operation of the racking device to unwind the cables.

8. In a multi-section flat knitting machine: a plurality of welt bars, one for each section; pairs of welt bar carrier devices, one pair for each welt bar and including welt bar holding members, lever arms carrying said members for tiltable swingable motion, and plates supporting said arms; a mechanism for advancing and retracting said welt bar carrier devices and including flexible cables, one attached to each supporting plate of the bar carrier devices, elongated channeled rails partly enclosing said cables, casings mounted for rocking movement and carrying said rails, drums within said casings and connected to said cables for winding and unwinding the same, a racking device for operating said drums to wind and unwind said cables, and a power driven means for actuating said racking device; a mechanism for lifting, tilting, and lowering the welt bar carrier devices including welt bar operating devices having means engageable with the welt bar holding members of the welt bar carrier devices for tilting and swinging said members together with the welt bar, and means in engagement with the rails of the welt bar carrier advancing and retracting mechanism for lifting and lowering the same; and a power driven means for actuating said welt bar actuating devices; a fabric draw-off device including a fabric draw-off member and means to move said draw-off member in a direction opposite to that of its draw-off movement; and, means for automatically actuating the draw-off member moving means simultaneously with the operation of the racking device to unwind the cables.

9. In a multi-section flat knitting machine: a plurality of welt bars, one for each section; pairs of welt bar carrier devices, one pair for each welt bar and including welt bar holding members, lever arms carrying said members for tiltable swingable motion and having a pair of camming surfaces, and plates supporting said arms; a mechanism for advancing and retracting said welt bar carrier devices and including flexible cables, one attached to each supporting plate of the bar carrier devices, elongated channeled rails partly enclosing said cables, casings mounted for rocking movement and carrying said rails, drums within said casings and connected to said cables for winding and unwinding the same, a racking device for operating said drums to wind and unwind said cables, and a power driven means for actuating said racking device; a mechanism for lifting, tilting, and lowering the welt bar carrier devices including welt bar operating devices having cam fingers engageable with the cam surfaces of the welt bar holding members of the welt bar carrier devices for tilting and swinging said members together with the welt bar, and means in engagement with the rails of the welt bar carrier advancing and retracting mechanism for lifting and lowering the same; and a power driven means for actuating said welt bar actuating devices; a fabric draw-off device including a fabric draw-off member and means to move

5 said draw-off member in a direction opposite to that of its draw-off movement; and, means for automatically actuating the draw-off member moving means simultaneously with the operation of the racking device to unwind the cables.

10. In combination with the main cam shaft and knitting instrumentalities of a flat knitting machine: a welt bar; carrier devices, one for each end of the welt bar, and including welt bar holding members, lever arms carrying said members for tiltable swingable motion, and plates supporting said arms; a mechanism for advancing and retracting said welt bar carrier devices towards and away from said knitting instrumentalities and including flexible cables, one attached to each supporting plate of the bar carrier devices, elongated channeled rails partly enclosing said cables, casings mounted for rocking movement and carrying said rails, drums within said casings and connected to said cables for winding and unwinding the same, a racking device for operating said drums to wind and unwind said cables, means for actuating said racking device, and a cam on said main cam shaft 15 for the operation of said racking device actuating means; a mechanism for lifting, tilting, and lowering the welt bar carrier devices in relation to said knitting instrumentalities and including welt bar operating devices having means engageable with the welt bar holding members of the welt bar carrier devices for tilting and swinging said members together with the welt bar, and means in engagement with the rails of the welt bar carrier advancing and retracting mechanisms 20 for lifting and lowering the same; means for actuating said welt bar actuating devices; and a cam on the main cam shaft for operating said last mentioned means; a fabric draw-off device including a fabric draw-off member and means to move said draw-off member in a direction opposite to that of its draw-off movement; and, means under control of the main cam shaft for automatically actuating the draw-off member moving means simultaneously with the operation 25 of the racking device to unwind the cables.

11. In combination with the main cam shaft and knitting instrumentalities of a flat knitting machine: a welt bar; carrier devices, one for each end of the welt bar, and including welt bar holding members, lever arms carrying said members for tiltable swingable motion, and having a pair of camming surfaces, and plates supporting said arms; a mechanism for advancing and retracting said welt bar carrier devices towards and away from said knitting instrumentalities and including flexible cables, one attached to each supporting plate of the bar carrier devices, elongated channeled rails partly enclosing said cables, casings mounted for rocking movement and carrying said rails, drums within said casings and connected to said cables for winding and unwinding the same, a racking device for operating said drums to wind and unwind said cables, means for actuating said racking device, and a cam on said main cam shaft for the operation of said racking device actuating means; a mechanism for lifting, tilting, and lowering the welt bar carrier devices in relation to said knitting instrumentalities and including welt bar operating devices having cam fingers engageable with the cam surfaces of the welt bar holding members of the welt bar carrier devices for tilting and swinging said members together with the welt bar, and means in engagement with the rails of the welt bar carrier advancing and retracting mechanisms for lifting

and lowering the same; means for actuating said welt bar actuating devices; and a cam on the main cam shaft for operating said last mentioned means; a fabric draw-off device including a fabric draw-off member and means to move said draw-off member in a direction opposite to that of its draw-off movement; and, means under control of the main cam shaft for automatically actuating the draw-off member moving means simultaneously with the operation of the racking device to unwind the cables.

12. In a flat knitting machine: a welt bar; separate carrier devices, one for each end of the welt bar, and operable to impart welt engaging, drawing, and turning movements to said welt bar, each of said carrier devices including a welt bar holding member, a lever arm carrying said member for tiltable, swingable motions, and a sliding plate supporting said arm to reciprocate the same together with said holding member and welt bar; a fabric draw-off device including a fabric draw-off member and means to move said draw-off member in a direction opposite to that of its draw-off movement; and, means for automatically actuating the draw-off member moving means simultaneously with the operation of the carrier devices to impart welt turning movement to the welt bar.

13. In a flat knitting machine: a welt bar; separate carrier devices one for each end of the welt bar; and a mechanism for advancing and retracting the welt bar carrier devices in unison, said mechanism including yieldable, flexible cables attached to the welt bar carrier devices, rigid guide members associated with said cables for guiding the same in a predetermined direction, drums connected with said cables for winding and unwinding the same, a rack device for operating said drums to wind and unwind the cables, and a power driven means for actuating said rack device; a fabric draw-off device including a fabric draw-off member and means to move said draw-off member in a direction opposite to that of its draw-off movement; and, means for automatically actuating the draw-off member moving means simultaneously with the operation of the rack device to unwind the cables.

14. In a flat knitting machine: a welt bar; separate carrier devices, one for each end of the welt bar; and a mechanism for advancing and retracting the welt bar carrier devices in unison, said mechanism including yieldable, flexible cables attached to the welt bar carrier devices, rigid guide members associated with said cables for guiding the same in a predetermined direction, drums connected with said cables for winding and unwinding the same, a rack device for operating said drums to wind and unwind the cables, a power driven means for actuating said rack device, and means adjustable for engagement with said rack device to limit the drum operating movement thereof; a fabric draw-off device including a fabric draw-off member and means to move said draw-off member in a direction opposite to that of its draw-off movement; and, means for automatically actuating the draw-off member moving means simultaneously with the operation of the rack device to unwind the cables.

15. In a welt forming attachment for knitting machines of the character described: a welt bar; carrier devices, one for each end of the welt bar; a mechanism operable for moving said welt bar carrier devices to draw and turn the welt fabric, said mechanism including movement imparting means, yieldable, flexible connecting cables be-

tween said movement imparting means and welt bar carrier devices for pulling and pushing the latter, and rigid guide members associated with said connecting cables for guiding the same in a predetermined direction in their pulling and pushing of the welt bar carrier devices; a fabric draw-off device including a fabric draw-off member and means to move said draw-off member in a direction opposite to that of its draw-off movement; and, means for automatically actuating the draw-off member moving means simultaneously with the pushing of the welt bar carrier devices by said mechanism.

16. In a welt forming attachment for knitting machines of the character described: a welt bar; carrier devices, one for each end of the welt bar; a mechanism operable for moving said welt bar carrier devices to draw and turn the welt fabric, said mechanism including movement imparting means, coil springs interconnecting said movement imparting means and welt bar carrier devices for pulling and pushing the latter, and rigid guide members associated with said coil springs for guiding the same in a predetermined direction in their pulling and pushing of the welt bar carrier devices; a fabric draw-off device including a fabric draw-off member and means to move said draw-off member in a direction opposite to that of its draw-off movement; and, means for automatically actuating the draw-off member moving means simultaneously with the pushing of the welt bar carrier devices by said mechanism.

17. In a flat knitting machine: a welt bar; separate carrier devices, one for each end of the welt bar; mechanism for advancing the welt bar carrier devices in unison; mechanism for lifting and lowering the welt bar carrier devices in unison; and mechanism for guiding the carrier devices in unison movement into a definite path when lowered and advancing, and for side-stepping said carrier devices in unison for movement into a definite path when lifted and advancing, said guiding and side-stepping mechanism including supporting brackets, and projecting elements on said brackets, certain of said elements being disposed to contact the carrier devices when moving in lowered position, and certain of said elements being disposed to contact the carrier devices when moving in lifted position; a fabric draw-off device including a fabric draw-off member and means to move said draw-off member in a direction opposite to that of its draw-off movement; and, means for automatically actuating the draw-off member moving means simultaneously with the advancing of the welt bar carrier devices.

18. In a flat knitting machine, a fabric take-up mechanism comprising, in combination with a welt rod: welt rod engaging elements; yieldable flexible cables attached to said elements; rigid guide members associated with said cables for guiding the same in a predetermined direction; a ware-roller engaging said cables and rotatable to wind and unwind the same; a rack device rotating said roller to unwind the cables; and a power driven means for actuating said rack device.

19. In a flat knitting machine, a fabric take-up mechanism comprising, in combination with a welt rod: welt rod engaging elements; yieldable flexible cables attached to said elements; rigid guide members associated with said cables for guiding the same in a predetermined direction; a torsional ware-roller engaging said cables and rotatable to wind and unwind the same; a rack

device rotating said torsional ware-roller to unwind the cables; and a power driven means for actuating said rack device.

20. In a flat knitting machine, the combination with the main cam shaft and the bank of bearded needles operated thereby: of a bank of welt hooks; mechanism operating to move said bank of welt hooks in a combined rectilinear path towards the needles and a curvilinear path over the needles to bring the welt hooks into engagement with the bearded side of said needles; and means operatively connecting said mechanism to the main cam shaft whereby said mechanism is operated in timed relation with the operation of said bank of needles; a fabric draw-off device including a fabric draw-off member and means to move said draw-off member in a direction opposite to that of its draw-off movement; and, means associated with said mechanism for automatically actuating the draw-off member moving means simultaneously with the movement of the bank of welt hooks towards the needles.

21. In a flat knitting machine, the combination with the main cam shaft and the bank of bearded needles operated thereby: of a bank of welt hooks; mechanism operating to move said bank of welt hooks in a combined continuous rectilinear horizontal path towards the needles and a curvilinear vertical path over and behind the needles on the bearded side thereof; and means operatively connecting said mechanism to the main cam shaft whereby said mechanism is operated in timed relation with the operation of said bank of needles; a fabric draw-off device including a fabric draw-off member and means to move said draw-off member in a direction opposite to that of its draw-off movement; and, means associated with said mechanism for automatically actuating the draw-off member moving means simultaneously with the movement of the bank of welt hooks towards the needles.

22. In a flat knitting machine, the combination with the main cam shaft and the bank of bearded needles actuated thereby: of a bank of welt hooks; mechanism operable to actuate said welt hooks in a combined rectilinear path towards said needles and a curvilinear path over the needles to bring the welt hooks into engagement with the bearded side of said needles; and cam means on the main cam shaft for operating said mechanism to actuate the welt hooks in timed relation with the actuation of said needles by the main cam shaft; a fabric draw-off device including a fabric draw-off member and means to move said draw-off member in a direction opposite to that of its draw-off movement; and, means associated with said mechanism for automatically actuating the draw-off member moving means simultaneously with the movement of the bank of welt hooks towards the needles.

23. In a flat knitting machine, the combination with the main cam shaft and the bank of bearded needles actuated thereby: of a bank of welt hooks; mechanism operable to actuate said welt hooks in a combined continuous rectilinear horizontal path towards said needles and a curvilinear vertical path over and behind the needles on the bearded side thereof; and cam means on the main cam shaft for operating said mechanism to actuate the welt hooks in timed relation with the actuation of said needles by the main cam shaft; a fabric draw-off device including a fabric draw-off member and means to move said draw-off member in a direction opposite to that of its draw-off movement; and, means associated

with said mechanism for automatically actuating the draw-off member moving means simultaneously with the movement of the bank of welt hooks towards the needles.

24. In a flat knitting machine, the combination with the main cam shaft, the bank of bearded needles, a set of knitting cams on the main cam shaft to actuate said needles during the knitting cycle of the machine, and a set of narrowing cams on the main cam shaft to actuate said needles during the narrowing cycle of the machine: of a bank of welt hooks; a mechanism operable to actuate said welt hooks in a combined rectilinear path towards the needles and a curvilinear path to bring the welt hooks into engagement with the bearded side of said needles; and cam means on the main cam shaft for operating said mechanism to actuate the welt hooks in timed relation with the actuation of said needles during the narrowing cycle of the machine by said set of narrowing cams on said main cam shaft; a fabric draw-off device including a fabric draw-off member and means to move said draw-off member in a direction opposite to that of its draw-off movement; and, means associated with said mechanism for automatically actuating the draw-off member moving means simultaneously with the movement of the bank of welt hooks towards the needles.

25. In a flat knitting machine, the combination with the main cam shaft, the bank of bearded needles, a set of knitted cams on the main cam shaft to actuate said needles during the knitting cycle of the machine, and a set of narrowing cams on the main cam shaft to actuate said needles during the narrowing cycle of the machine; of a bank of welt hooks; a mechanism operable to actuate said welt hooks in a combined rectilinear path towards the needles and a curvilinear path over and behind the needles on the bearded side thereof; and cam means on the main cam shaft for operating said mechanism to actuate the welt hooks in timed relation with the actuation of said needles during the narrowing cycle of the machine by said set of narrowing cams on said main cam shaft; a fabric draw-off device including a fabric draw-off member and means to move said draw-off member in a direction opposite to that of its draw-off movement; and, means associated with said mechanism for automatically actuating the draw-off member moving means simultaneously with the movement of the bank of welt hooks towards the needles.

26. In a flat knitting machine having a bank of bearded needles and a main cam shaft for actuating said needles, a welt forming attachment comprising: a bank of welt hooks; mechanism operatively associated with said hooks to actuate the same in a rectilinear path towards said needles and in a curvilinear path to bring the welt hooks into engagement with the bearded side of said needles; and cam means on the main cam shaft operatively associated with said mechanism for operating the same to actuate the welt hooks in timed relation with the actuation of said needles by the main cam shaft; a fabric draw-off device including a fabric draw-off member and means to move said draw-off member in a direction opposite to that of its draw-off movement; and, means associated with said mechanism for automatically actuating the draw-off member moving means simultaneously with the movement of the bank of welt hooks towards the needles.

27. In a flat knitting machine having a bank

of bearded needles and a main cam shaft for actuating said needles, a welt forming attachment comprising: a bank of welt hooks; mechanism operatively associated with said hooks to actuate the same in a rectilinear path towards said needles and in a curvilinear path over and behind said needles on the bearded side thereof; and cam means on the main cam shaft operatively associated with said mechanism for operating the same to actuate the welt hooks in timed relation with the actuation of said needles by the main cam shaft; a fabric draw-off device including a fabric draw-off member and means to move said draw-off member in a direction opposite to that of its draw-off movement; and, means associated with said mechanism for automatically actuating the draw-off member moving means simultaneously with the movement of the bank of welt hooks towards the needles.

28. In a flat knitting machine having a bank of bearded needles and a main cam shaft for actuating said needles, a welt forming attachment comprising: a bank of welt hooks; and mechanism associated with the main cam shaft and connected to said hooks to actuate the same in a rectilinear path towards said needles and in a curvilinear path to bring the welt hooks into engagement with the bearded side of said needles in timed relation with the actuation of said needles by the main cam shaft; a fabric draw-off device including a fabric draw-off member and means to move said draw-off member in a direction opposite to that of its draw-off movement; and, means associated with said mechanism for automatically actuating the draw-off member moving means simultaneously with the movement of the bank of welt hooks towards the needles.

29. In a flat knitting machine having a bank of bearded needles and a main cam shaft for actuating said needles, a welt forming attachment comprising: a bank of welt hooks; and mechanism operatively associated with the main cam shaft and connected to said hooks to actuate the same in a rectilinear path towards said needles and in a curvilinear path over and behind the needles on the bearded side thereof in timed relation with the actuation of said needles by the main cam shaft; a fabric draw-off device including a fabric draw-off member and means to move said draw-off member in a direction opposite to that of its draw-off movement; and, means associated with said mechanism for automatically actuating the draw-off member moving means simultaneously with the movement of the bank of welt hooks towards the needles.

30. In a flat knitting machine, a needle bar having a bank of bearded needles; a main cam shaft controlling the actuation of said needles; a welt bar having welt hooks adapted for cooperation with the needles on the needle bar; mechanism operable to actuate the welt bar in a rectilinear motion towards the needles and in a curvilinear motion to bring the welt hooks on the welt bar into engagement with the bearded side of the needles on the needle bar; and means establishing a direct connection between the main cam shaft and said mechanism for operating the latter to actuate the welt bar in timed relation with the actuation of the needle bar; a fabric draw-off device including a fabric draw-off member and means to move said draw-off member in a direction opposite to that of its draw-off movement; and, means operable for automatically actuating the draw-off member moving means simultaneously with the movement of the welt bar in the direction towards the needles.

actuating the draw-off member moving means simultaneously with the movement of the welt bar in the direction towards the needles.

31. In a flat knitting machine, a needle bar having a bank of bearded needles; a main cam shaft controlling the actuation of said needles; a welt bar having welt hooks adapted for cooperation with the needles on the needle bar; mechanism operable to actuate the welt bar in a rectilinear motion towards the needles and in a curvilinear motion over and behind said needles on the bearded side thereof; and means establishing a direct connection between the main cam shaft and said mechanism for operating the latter to actuate the welt bar in timed relation with the actuation of the needle bar; a fabric draw-off device including a fabric draw-off member and means to move said draw-off member in a direction opposite to that of its draw-off movement; and, means operable for automatically actuating the draw-off member moving means simultaneously with the movement of the welt bar in the direction towards the needles.

32. In a flat knitting machine, a needle bar having a bank of bearded needles; a main cam shaft; cam means on said shaft for actuating said needle bar; a welt bar having welt hooks adapted for cooperation with the needles of the needle bar; mechanism operable to actuate the welt bar in a rectilinear motion towards the needles of the needle bar and in a curvilinear motion to bring the welt hooks on the welt bar into engagement with the bearded side of the needles on the needle bar; and other cam means on the main cam shaft, said other cam means being operatively associated with said mechanism and acting thereon for operating the same to actuate the welt bar in timed relation with the actuation of the needle bar by said first mentioned cam means on the main cam shaft; a fabric draw-off device including a fabric draw-off member and means to move said draw-off member in a direction opposite to that of its draw-off movement; and, means operable for automatically actuating the draw-off member moving means simultaneously with the movement of the welt bar in the direction towards the needles.

33. In a flat knitting machine, a needle bar having a bank of bearded needles; a main cam shaft; cam means on said shaft for actuating said needle bar; a welt bar having welt hooks adapted for cooperation with the needles of the needle bar; mechanism operable to actuate the welt bar in a rectilinear motion towards the needles of the needle bar and in a curvilinear motion over and behind said needles on the bearded side thereof; and other cam means on the main cam shaft, said other cam means being operatively associated with said mechanism and acting thereon for operating the same to actuate the welt bar in timed relation with the actuation of the needle bar by said first mentioned cam means on the main cam shaft; a fabric draw-off device including a fabric draw-off member and means to move said draw-off member in a direction opposite to that of its draw-off movement; and, means operable for automatically actuating the draw-off member moving means simultaneously with the movement of the welt bar in the direction towards the needles.

34. In combination with the bank of needles and main cam shaft of a flat knitting machine: a welt bar having a bank of welt hooks; carriers on which the welt bar is mounted to receive

bodily tilting movements in reverse directions over the needles; swinging arms on which the carriers are slidably mounted to receive sliding movements towards and away from the needles, said arms being mounted to receive lifting and lowering movements; means operated by the main cam shaft to cause lifting and lowering movements of the arms whereby to lift and lower the carriers of the welt bar; and means also operated by the main cam shaft for sliding the carriers in unison upon said arms; a fabric draw-off device including a fabric draw-off member and means to move said draw-off member in a direction opposite to that of its draw-off movement; and, means for automatically actuating the draw-off member moving means simultaneously with the sliding movement of the carriers towards the needles.

35. In combination with the bank of needles and main cam shaft of a flat knitting machine: a welt bar having a bank of welt hooks; carriers on which the welt bar is mounted to receive bodily tilting movements in reverse directions over the needles; swinging arms on which the carriers are slidably mounted to receive sliding movements towards and away from the needles, said arms being mounted to receive lifting and lowering movements; means operated by the main cam shaft to cause lifting and lowering movements of the arms whereby to lift and lower the carriers of the welt bar; means also operated by the main cam shaft for sliding the carriers in unison upon said arms; and means likewise controlled by the main cam shaft for tilting the carriers; a fabric draw-off device including a fabric draw-off member and means to move said draw-off member in a direction opposite to that of its draw-off movement; and, means for automatically actuating the draw-off member moving means simultaneously with the sliding movement of the carriers towards the needles.

36. In combination with the bank of bearded needles of a flat knitting machine, a welt turning mechanism comprising: a welt bar; carrier devices, one for each end of the welt bar; and mechanism operable for positive action on the welt bar carrier devices for positively moving the welt bar in a rectilinear path towards and away from the needles during and for the picking-up phase of the initial course of loops and the knitting of the welt fabric on the knitting machine, and for positively moving the welt bar in a horizontal side-step and curvilinear motion towards and behind the needles to engage said hooks with the bearded side of the needles for and during the transfer phase of the initial course of loops of the welt; a fabric draw-off device including a fabric draw-off member and means to move said draw-off member in a direction opposite to that of its draw-off movement; and, means for automatically actuating the draw-off member moving means simultaneously with the movement of the carrier devices towards the needles during the transfer phase of the initial course of loops of the welt.

37. In a flat knitting machine having a plurality of knitting sections and provided with a main cam shaft: a welt bar for each knitting section having a bank of welt hooks; carriers on which the welt bars are mounted to receive tilting movements in reverse directional supports on which the carriers are mounted to receive sliding movements towards and away from the needles, said supports being mounted to receive lifting and lowering movements; mechanism op-

erated by the main cam shaft for sliding the carriers on their supports towards the needles; mechanism also operated by the main cam shaft for lifting and lowering said supports; and means in each knitting section of the knitting machine operable to side-step the welt bar during the loop receiving stage of the welt formation for adjusting the welt hooks in mid space positions between the needle planes, and to side-step reversely the welt bar during the loop delivering stage for adjusting the welt hooks into the planes of the needles; a fabric draw-off device including a fabric draw-off member and means to move said draw-off member in a direction opposite to that of its draw-off movement; and, means for automatically actuating the draw-off member moving means simultaneously with the sliding movement of the carriers towards the needles.

38. In combination with the bank of needles in each knitting section, and the main cam shaft of a flat knitting machine: a welt bar for each section having a bank of welt hooks; carriers on which the welt bars are mounted to receive tilting movements in reverse directions; supports on which the carriers are mounted to receive sliding movements towards and away from the needles, said supports being mounted to receive lifting and lowering movements; mechanism operated by the main cam shaft for sliding the carriers on their supports towards the needles; mechanism also operated by the main cam shaft for lifting and lowering said supports; and welt bar laterally adjusting means in each knitting section of the knitting machine operable to side-step the welt bar during the loop receiving stage of the welt formation for adjusting the welt hooks in mid space positions between the needle planes, and to side-step reversely the welt bar during the loop delivering stage for adjusting the welt hooks into the planes of the needles; a fabric draw-off device including a fabric draw-off member and means to move said draw-off member in a direction opposite to that of its draw-off movement; and, means for automatically actuating the draw-off member moving means simultaneously with the sliding movement of the carriers towards the needles.

39. In a flat knitting machine having a bank of needles: a welt turner including a welt bar and means to move the welt bar towards the needles; a draw-off mechanism including a fabric draw-off member and means to move said draw-off member in a direction opposite to that of its draw-off movement; and means operable for actuating both said welt bar and draw-off member moving means.

40. In a flat knitting machine having a bank of needles and a main cam shaft: a welt turner including a welt bar and means to move the welt bar towards the needles; a draw-off mechanism including a fabric draw-off member and means to move said draw-off member in a direction opposite to that of its draw-off movement; and means operated by the main cam shaft for actuating both said welt bar and draw-off member moving means.

41. In a flat knitting machine having a bank of needles: a welt turner including a welt bar and means to move the welt bar towards the needles; a draw-off mechanism including a fabric draw-off member and means to move said draw-off member in a direction opposite to that of its draw-off movement; and a mechanism common to both said welt bar and said draw-off member moving means for actuating the same.

42. In a flat knitting machine having a bank of needles and a main cam shaft: a welt turner including a welt bar and means to move the welt bar towards the needles; a draw-off mechanism including a fabric draw-off member and means to move said draw-off member in a direction opposite to that of its draw-off movement; and a mechanism operated by the main cam shaft and common to both said welt bar and draw-off member moving means for actuating the same.

43. In combination with a welt turning attachment for flat knitting machines, a take-up attachment comprising: a tensioning draw-off mechanism for applying tension of the welt fabric being knitted on the knitting machine; and means for automatically controlling the operation of said mechanism in timed relation with the welt turning attachment to release the tension of said mechanism on the knitted welt fabric simultaneously with the welt turning function of said welt turning attachment.

44. In a flat knitting machine, the combination with the main cam shaft and a bank of needles operated thereby: of a bank of welt hooks; mechanism operating to move said bank of welt hooks in a horizontal rectilinear path towards and away from the needles; means cofunctioning with said mechanism for moving the welt hooks in a curvilinear path over and behind the needles as a continuation of the movement in a horizontal rectilinear path and, simultaneously therewith, variably changing the angular relationship of the hooks with the needles; and means operatively connecting said mechanism and means to the main cam shaft whereby said mechanism and means are operated in timed relation with the operation of said bank of needles; a fabric draw-off device including a fabric draw-off member and means to move said draw-off member in a direction opposite to that of its draw-off movement; and, means associated with said mechanism for automatically actuating the draw-off member moving means simultaneously with the movement of the bank of welt hooks towards the needles.

45. In a flat knitting machine, the combination with the main cam shaft and a bank of bearded needles operated thereby: of a bank of welt hooks; mechanism operating to move said bank of welt hooks in a horizontal rectilinear path towards and away from the needles; means co-functioning with said mechanism for moving the welt hooks in a curvilinear path over and behind the needles as a continuation of the movement in a horizontal rectilinear path and, simultaneously therewith, variably changing the angular relationship of the hooks with the needles; and cam means on the main cam shaft for operating said mechanism and means to actuate the welt hooks in timed relation with the operation of said needles by the main cam shaft; a fabric draw-off device including a fabric draw-off member and means to move said draw-off member in a direction opposite to that of its draw-off movement; and, means associated with said mechanism for automatically actuating the draw-off member moving means simultaneously with the movement of the bank of welt hooks towards the needles.

46. In a flat knitting machine, the combination with the main cam shaft and the bank of bearded needles operated thereby: of a bank of welt hooks adapted to engage and remove loops from the needles and subsequently return said loops to the needles; mechanism operating to move said welt

hooks in a rectilinear horizontal path towards and away from said needles to engage and remove the loops therefrom, then in a combined rectilinear path towards the needles and curvilinear path over and behind the needles to position the welt hooks on the bearded side of the needles thereby returning the loops to the needles, then in a curvilinear path behind the needles towards the bearded side thereof to disengage said hooks from the loops returned on the needles, then in a reverse curvilinear path over the needles to place the disengaged welt hooks in front of said needles, and finally in a rectilinear path away from the needles; and means operatively connecting said mechanism to the main cam shaft whereby said mechanism is operated in timed relation with the operation of said bank of needles; a fabric draw-off device including a fabric draw-off member and means to move said draw-off member in a direction opposite to that of its draw-off movement; and, means associated with said mechanism for automatically actuating the draw-off member moving means simultaneously with the movement of the bank of welt hooks towards the needles.

47. In a flat knitting machine, the combination with the main cam shaft and the bank of bearded needles operated thereby: of a bank of welt hooks adapted to engage and remove loops from the needles and subsequently return said loops to the needles; mechanism operating to move said welt hooks in a rectilinear horizontal path towards and away from said needles to engage and remove the loops therefrom, then in a combined rectilinear path towards the needles and curvilinear path over and behind the needles to position the welt hooks on the bearded side of the needles thereby returning the loops to the needles, then in a curvilinear path behind the needles towards the bearded side thereof to disengage said hooks from the loops returned on the needles, then in a reverse curvilinear path over the needles to place the disengaged welt hooks in front of said needles, and finally in a rectilinear path away from the needles; and cam means on the main cam shaft for operating said mechanism to move the welt hooks in timed relation with the operation of said needles on the main cam shaft; a fabric draw-off device including a fabric draw-off member and means to move said draw-off member in a direction opposite to that of its draw-off movement; and, means associated with said mechanism for automatically actuating the draw-off member moving means simultaneously with the movement of the bank of welt hooks towards the needles.

48. A combined welt turning and take-up attachment for flat knitting machines comprising, in combination with a welt bar and a welt rod: a welt bar mechanism and a welt rod mechanism; said welt bar mechanism including a carrier device for each end of the welt bar, and movement imparting means having a take-up shaft and yieldable means attached to the take-up shaft and connected to said carrier devices; said welt rod mechanism including a welt rod engaging element for each end of the welt rod, and movement imparting means having a wareroller shaft and yieldable means attached to the wareroller shaft and connected to said welt rod engaging elements to move the welt rod in a draw-off direction, and means associated with the wareroller shaft to automatically move the same in a direction to relieve the welt rod in its draw-off action.

49. A combined welt turning and take-up attachment for flat knitting machines comprising, in combination with a welt bar and a welt rod: a welt bar mechanism and a welt rod mechanism; said welt bar mechanism including a carrier device for each end of the welt bar, and movement imparting means having a take-up shaft and yieldable means in the form of coil springs attached at one end to the take-up shaft and connected to the carrier devices; said welt rod mechanism including a welt rod engaging element for each end of the welt rod, movement imparting means having a wareroller shaft and yieldable means in the form of coil springs attached at one end to the wareroller shaft and connected at the other end to said welt rod engaging elements; and automatic fabric draw-off releasing means operatively associated with said wareroller shaft.

50. A combined welt turning and take-up attachment for flat knitting machines comprising, in combination with a welt bar and a welt rod: a welt bar mechanism and a welt rod mechanism; said welt bar mechanism including a carrier device for each end of the welt bar, and movement imparting means having a take-up shaft and yieldable means attached to the take-up shaft and connected to said carrier devices; said welt rod mechanism including a welt rod engaging element for each end of the welt rod, and movement imparting means having a wareroller shaft and yieldable means attached to the wareroller shaft and connected to said welt rod engaging elements; and mechanism for automatically controlling the operation of said welt bar mechanism and welt rod mechanism.

51. A combined welt turning and take-up attachment for flat knitting machines comprising, in combination with a welt bar and a welt rod: a welt bar mechanism and a welt rod mechanism; said welt bar mechanism including a carrier device for each end of the welt bar, and movement imparting means having a take-up shaft and yieldable means in the form of coil springs attached at one end to the take-up shaft and connected to the carrier devices; said welt rod mechanism including a welt rod engaging element for each end of the welt rod, movement imparting means having a wareroller shaft and yieldable means in the form of coil springs attached at one end to the wareroller shaft and connected at the other end to said welt rod engaging elements; and mechanism for automatically controlling the operation of said welt bar mechanism and welt rod mechanism.

52. In a flat knitting machine provided with a main cam shaft, the combination with a welt bar and a welt rod of a combined welt turning and take-up attachment comprising: a welt bar operating mechanism including a take-up shaft rotatable in one direction to draw the welt; a welt rod operating mechanism including a wareroller shaft rotatable in one direction to tension the welt; means engageable with the take-up shaft and with the wareroller shaft and operable to rotate said shafts in their reverse directions for the turning of the welt and the simultaneous release of its tension; and a single cam on the main cam shaft for operating said means.

53. In a flat knitting machine provided with a main cam shaft and a pattern control shifting rod, the combination with a welt bar and a welt

rod of a combined welt turning and take-up attachment comprising: a welt bar operating mechanism including a take-up shaft rotatable in one direction to draw the welt; a welt rod operating mechanism including a wareroller shaft rotatable in one direction to tension the welt; means engageable with the take-up shaft and with the wareroller shaft and operable to rotate said shafts in their reverse directions for the turning of the welt and the simultaneous release of its tension; a single cam on the main cam shaft for operating said means; and means connected to the pattern control shifting rod and associated with the means engageable with said shafts for governing the operation of the latter by said cam.

54. In a flat knitting machine provided with a main cam shaft, a combined welt turning and take-up attachment comprising, in combination with a welt bar and a welt rod: a welt bar mechanism and a welt rod mechanism; said welt bar mechanism including a carrier device for each end of the welt bar, and movement imparting means having a take-up shaft and yieldable means attached to the take-up shaft and connected to said carrier devices, said take-up shaft being rotatable in one direction to draw the welt; said welt rod mechanism including a welt rod engaging element for each end of the welt rod, and movement imparting means having a wareroller shaft and yieldable means attached to the wareroller shaft and connected to said welt rod engaging elements, said wareroller shaft being rotatable in one direction to tension the welt; means engageable with the take-up shaft and with the wareroller shaft and operable to rotate said shafts in their reverse directions for turning the welt and simultaneously releasing the latter of its tension; and a single cam on the main cam shaft for operating the last mentioned means.

55. In a flat knitting machine provided with a main cam shaft and a pattern control shifting rod, a combined welt turning and take-up attachment comprising, in combination with a welt bar and a welt rod: a welt bar mechanism and a welt rod mechanism; said welt bar mechanism including a carrier device for each end of the welt bar, and movement imparting means having a take-up shaft and yieldable means attached to the take-up shaft and connected to said carrier devices, said take-up shaft being rotatable in one direction to draw the welt; said welt rod mechanism including a welt rod engaging element for each end of the welt rod, and movement imparting means having a wareroller shaft and yieldable means attached to the wareroller shaft and connected to said welt rod engaging elements, said wareroller shaft being rotatable in one direction to tension the welt; means engageable with the take-up shaft and with the wareroller shaft and operable to rotate said shafts in their reverse directions for turning the welt and simultaneously releasing the latter of its tension; a single cam on the main cam shaft for operating the last mentioned means; and means connected to the pattern control shifting rod and associated with the means engageable with said shafts for governing the latter by said cam.
